UNITED STATES PATENT OFFICE.

JOHN KENNEDY, OF MONTREAL, CANADA.

APPARATUS FOR HOLDING DREDGES IN PLACE.

SPECIFICATION forming part of Letters Patent No. 447,717, dated March 3, 1891.

Application filed May 12, 1890. Renewed February 9, 1891. Serial No. 380,727. (No model.)

To all whom it may concern:

Be it known that I, JOHN KENNEDY, civil engineer, of the city of Montreal, in the district of Montreal and Province of Quebec, Canada, have invented certain new and useful Improvements in Apparatus for Holding Dredges in Place; and I do hereby declare that the following is a full, clear, and exact description of the same.

My invention relates to the means by which the spuds of dipper-dredges are held in place at any height relatively to the hull, and provides a device by which they may be secured at the point desired and the movement of the spud controlled. It may be thus briefly described: Across the face of the spud are placed at any suitable height and in recesses formed on the faces of the guide-posts bars or plates, and across the inner side of these guide-posts at the same level is arranged a clamping-plate, which, with the two bars, is secured to the guide-posts by screw-bolts passing through them. On the inner side of this clamping-plate is mounted at some little distance from it a plate secured in place by bolts passing through the clamping-plate and bars. On this plate is formed a threaded seat, in which works a screw acting against the clamping-plate. To the inner face of the spud are secured one or more plates or straps attached thereto by any suitable means. These pass down between the horizontal bars and between the inner one and the clamping-plate, just sufficient play being given to allow them to pass easily up and down. It will be seen that to stop the vertical movement of the spud and secure it at the point desired all that is needed is to turn the screw and press the horizontal bars and vertical straps together, and thus hold the vertical straps and the spud fast, or by modifying the pressure control the rate of its movement.

In the drawings hereto annexed and forming part of this specification, Figure 1 is a perspective view of the spud and guide-posts at one side of the bow of the dredge; Fig. 2, a vertical side elevation and part sectional view of same; Fig. 3, a front elevation, and Fig. 4

a horizontal section, of same on line Z Z, Fig. 2. 50

Like symbols denote the same parts.

A is a hull of the dredge, and B B the two guide-posts, these being recessed on their inner faces, as shown at b b, and C is the spud.

D D' are the horizontal bars of steel or iron 55 set in the recesses b b, and E the clamping-plate, d d being bolts passing through these and the guide-posts.

F F' are straps or plates secured on the inner face of the spud and running nearly its 60 whole length. These pass as is shown, F between the bars D D' and F' between the bar D' and plate E, being so arranged that while close together the straps will slide easily up and down. Blocks d' d' may be inserted between 65 the ends of the plates D, D', and E, so as to prevent them from being brought into close proximity to each other by the clamping device, to be presently described.

G is a plate secured in place by bolts g, 70 passing loosely through the plate E and bar D' and secured in bar D.

In the threaded seat G' works a turn-screw H, bearing against the clamping-plate E at the point of intersection of the bars D D' and 75 straps F F'. By turning this screw the plate, bars, and straps are clamped and pressed together, the meeting surfaces of the former coming into actual contact with those of the latter and gripping them and holding them 80 fast, and, if desired, this arrangement may be applied to more than one side of the spud.

The horizontal bars or plates may be attached to or carried by the guide-posts, or be supported upon any suitable frame, &c., 85 mounted upon the deck of the dredge. Any means other than the screw may be used to clamp the horizontal bars and vertical straps together, and if more than one strap be used the one nearest the spud may be secured to it 90 or caused to bear against it by clamping.

Having thus described my invention, I beg to state that what I claim is as follows:

1. In apparatus for holding dredges, the combination of the following elements, viz: 95 horizontal bars or plates secured to the guide-

posts or carried on and connected with the hull of the dredge, a vertical strap or straps secured to the spud and passing between such bars, and means for holding such straps and bars together at any desired point, all as herein described.

2. The combination of the guide-posts B B, bars D D', and clamping-plate E, attached

thereto, straps F F', secured to spud C and passing between such clamps, and screw H, ¹⁰ working in plate G and against clamp E, all substantially as herein set forth.

JOHN KENNEDY.
